of Japan

Application December 2, 1955, Serial No. 550,666

3 Claims. (Cl. 80—6)

This invention relates in general to a continuously operating, fully automatic machine for cold rolling threads into a plurality of screw blanks and, more particularly, to a type thereof wherein the threads are produced upon said blanks by advancing them between the spaced peripheries of a pair of radially aligned, cylindrical dies.

This application is a continuation-in-part of my application Serial No. 509,957, filed May 20, 1955, and entitled "Continuous Thread Cold Rolling Process and Machine," now abandoned. As stated in said co-pending application Serial No. 509,957, several machines and methods have been developed for cold rolling threads, particularly on screw blanks. However, insofar as I am aware, the present thread rolling machines which have a high output capacity produce inferior threads, and those present machines, which produce high quality, rolled threads, have a relatively low output capacity. Thus, insofar as I am aware, a cold thread rolling machine capable of continuously producing large quantities of high quality screw threads at a rapid output rate has not been produced prior to my invention disclosed herein.

Attempts have been made in the past to produce such a machine, as demonstrated by the Landis Patent No. 1,107,621, issued in 1914. However, although the Landis patent expired more than twenty years ago, the machine represented by the Landis patent has never, so far as I know, received commercial acceptance. It is my belief that this non-use is due to the inability of previous machine like the Landis machine to produce high quality screw threads at a rapid rate.

Accordingly, a primary object of this invention is the provision of a relatively small, compact machine of great strength and durability, for automatically and continuously producing high quality screw threads upon a plurality of successively fed blanks at a relatively high rate of output, said machine being of the type having a pair of radially aligned, cylindrical die rollers peripherally spaced from each other and rotatable in the same direction upon substantially parallel axes.

A further object of this invention is the provision of a machine, as aforesaid, wherein the die rollers have different peripheral speeds, wherein guide mechanism is provided for conveying screw blanks to a point between the die rolls and said guide mechanism moves between said rolls at speed substantially equal to one-half the difference in said peripheral speeds, and wherein means is provided whereby the screw blanks will move and be advanced between said rolls slightly faster than said speed of said guide mechanism, thereby preventing injury to the expanding diameter of the screw blank as the thread is being rolled thereinto.

A further object of this invention is the provision of a thread rolling machine, as aforesaid, having adjustment means for momentarily increasing or decreasing the speed of movement of said guide mechanism between said die rolls for the purpose of adjusting and controlling the

2

phase or peripheral relationship of said die rollers with respect to the screw blanks being threaded thereby.

A further object of this invention is the provision of a thread rolling machine, as aforesaid, whereby threads of various pitches and pitch diameters may be produced by changing the die rollers and the distance between the axes thereof, but, however, wherein the distance between said rollers, once established for any given screw thread, is maintained substantially constant, within close tolerances, throughout the entire continuous operation of a machine, thereby eliminating the need for any type of device for reciprocating one of said rollers with respect to the other during any part of the thread rolling operation.

15 Other objects and purposes of this invention will become apparent to persons familiar with this type of machine upon reading the following specification and examining the accompanying drawings, in which:

Figure 1 is a top plan view of said thread rolling machine, embodying my invention.

Figure 2 is the side elevation view of said machine, including a support base therefor.

Figure 3 is a sectional view, taken along the line III—III of Figure 1.

25 Figure 4 is a sectional view, taken along the line IV—IV of Figure 1.

Figure 5 is a sectional view, taken along the line V—V of Figure 2.

Figure 6 is a sectional view, taken along the line VI—VI of Figure 3.

Figure 7 is a sectional view, taken along the line of VII—VII of Figure 3.

Figure 8 is a sectional view, substantially as taken along the line VIII—VIII of Figure 1.

35 Figure 9 is a sectional view, taken along the line IX—IX of Figure 4.

Figure 10 is a sectional view, taken along the line X—X of Figure 9.

Figure 11 is an overlay of opposing portions of the 40 peripheries of a pair of die rolls, with said peripheries distorted into planar positions.

Figure 12 is a side elevation view of a portion of a threaded screw with the screw blank from which it was rolled shown in broken lines.

45 Figure 13 is an overlay of the corresponding portions of the peripheries of said die rolls engaged by the screw shown in Figure 12 during a 180° rotation thereof.

For the purpose of convenience in description, the 50 terms "front," "rear," and derivatives thereof, will have reference to the leftward and rightward ends of the machine as appearing in Figure 1. The terms "upper," "lower," and derivatives thereof, will have reference to the machine as appearing in Figure 2. The terms "left," "right," and derivatives thereof, will have reference to the machine as appearing in Figure 4. The terms "inner," "outer," and derivatives thereof, will have reference to the geometric center of said machine and parts thereof.

General description

60 In order to meet the objects and purposes set forth above, as well as others related thereto, I have provided an automatic machine 10 (Figures 1 and 2) for cold rolling threads into a plurality of cylindrical blanks continuously fed to, and advanced between, the spaced, radially aligned peripheries of a pair of cylindrical die rolls 11 and 12 forming a part of said machine. The die rolls 11 and 12, which are rotated in the same direction, are supported by the housings 13 and 14, which are in turn mounted upon the machine base 15. A cylindrical feed shell 16, which concentrically surrounds one of said die rolls, is provided with a plurality of slots 17 there-

through for receiving said cylindrical blanks and feeding them between said die rolls at a preselected speed which varies with the difference between the peripheral speeds of said die rolls 11 and 12.

Detailed construction

As shown in Figures 1 and 4, the housings 13 and 14 of the thread rolling machine 10 contain substantially parallel, die supporting shafts 21 and 22, respectively. In this particular embodiment, the housing 13 is releasably secured to the base 15 by means, such as the bolts 18. When the bolts 18 are loosened, housing 13 is pivotable with respect to said base about the pivot pin 20 for the purpose of adjusting the axis of the shaft 21 with respect to the axis of the shaft 22. The housing 14 is releasably secured upon the base 15 by means of the transverse guide rails 23 and 24 and the clamping members 25 and 26 and adjustably movable toward and away from the housing 13. A pair of parallel, transverse tie rods 27 and 28 are secured upon, and extend through, the housings 13 and 14 above and below, respectively, the shafts 21 and 22. Said tie rods 27 and 28 are threaded at their opposite ends and engaged by internally threaded locking collars 29 for positioning and holding the housing 14 with respect to the housing 13 in a substantially conventional manner.

The rear ends of the housings 13 and 14 are provided with gear boxes 31 and 32 for connecting the die shafts 21 and 22, respectively, to a transverse power shaft 33 in a conventional manner, said power shaft being driven by any convenient means, not shown. Thus, by appropriate selection of gear ratios in the gear boxes 31 and 32, said die shafts 21 and 22 may be rotated at the same or different rotational speeds, as desired or required. In this particular embodiment, said shafts 21 and 22 rotate at different rotational speeds.

The die rolls 11 and 12 are mounted upon, and rotatable with, the die shafts 21 and 22, respectively, near the forward ends thereof and forwardly of the housings 13 and 14. A pair of coupling heads 34 and 35 are rotatably supported upon the extreme front ends of said die shafts 21 and 22, respectively, and are adjustably connected to each other by a pair of parallel connecting rods 36 and 37, which are substantially parallel with the tie rods 27 and 28. As will be seen hereinafter, the heads 34 and 35 and the rods 27, 28, 36 and 37 oppose lateral movement of the die shafts 21 and 22 away from each other during the thread rolling operation, that is, when a blank is passing between the die rolls 11 and 12.

An external gear 40 (Figure 3) is mounted upon, and rotatable with, the die shaft 22, adjacent to the rearward face of the die roller 12. A planet carrier 38, which encircles the gear 40, rotatably supports a plurality of planet gears 39 uniformly spaced around the perimeter of said gear 40. Said planet gears 39 are simultaneously engaged by the internal teeth 41 and 42 of a pair of adjacent internal gears 43 and 44, respectively. The rear ring gear 44 also has external teeth 45, which are engageable with a worm 46 (Figure 4) rotatably mounted upon the housing 14 with its axis in a vertical position. The worm 46 is secured upon a vertical shaft 47 having an adjusting head 48 at the upper end thereof.

The front ring gear 43 is secured to, and rotatable with, the feed shell 16. The feed shell 16 is provided with a plurality of elongated slots 17, which are preferably parallel with each other and with the axis of the die shaft 22. Said slots 17 are disposed uniformly along the periphery of the feed shell 16 and preferably extend completely across that portion of the shell which passes between the die rolls 11 and 12. Said feed shell 16 is of such thickness that it will pass between said die rolls 11 and 12 without interference of any kind therewith. Means, such as the chute 30, is provided for feeding screw blanks 50 from a source, not shown, into the slots 17 in the feed shell 16.

As shown in Figure 7, the internal teeth 41 on the front

ring gear 43 have a different pitch than the internal teeth 42 on the rear ring gear 44, even though both ring gears engage the same planet gears 39 simultaneously. The rear ring gear 44 is normally held in fixed position by its engagement with the worm 46. Thus, rotation of the external gear 40 rotates the planet gears 39 within said ring gears 43 and 44 and thereby effects a circumferential advancement, herein referred to as a profile shift, of the front ring gear 43 with respect to the rear ring gear 44. The said profile shift of the front ring gear 43 may be varied by varying the difference between the pitches of the two sets of internal teeth 41 and 42. This profile shift of the front ring gear 43 is selected so that the feed shell 16 will have a peripheral speed approximately equal to one-half the difference between the peripheral speeds of the die rolls 11 and 12.

Ordinarily, the feed shell 16 will encircle that die roll, here the right roll 12, whose periphery moves downwardly between the two rolls. In this case, die roll 12 will normally be the faster moving roll, so that said shell 16 will be moving downwardly between said die rolls and the feeding operation will not be opposed by gravity. However, this is a matter of choice and feeding could be directed upwardly, if desired. Also, the shell 16 may encircle the slower moving die, here the die 11, and, by proper selection of the teeth 41 and 42, the shell 16 may be caused to rotate counter to the die 11 and produce the same downward feeding. In any event, the direction of movement of the shell 16 between the die rolls will always be the same as the direction of movement of the faster moving one of said peripheries between said rolls.

The peripheries of the die rolls 11 and 12 are each provided with a plurality of helical grooves 51 (Figures 9, 10, 11 and 13), having the same pitch and depth as the thread which they will produce upon the cylindrical blank 50 passing therebetween. The slope of said helical grooves 51 with respect to a plane 49 (Figure 11) passing perpendicularly through the axes of the die rolls 11 and 12 will, in this particular embodiment, be identical on both die rolls, even though said rolls will have different peripheral speeds. Thus, as shown in Figures 11 and 13, the helical grooves 51 on one die roll (in solid lines) will intersect the grooves on the other die roll (in broken lines), when superimposed upon each other, at points defining parallel lines "a," which are substantially parallel with the axes of said rolls. It will be observed that there will be two lines "a" of intersecting points for each start "b" of a helical groove 51 along one edge of a die roll. The number of starts "b" on a particular die roll, hence the slope of said helical grooves 51, will depend upon the pitch of the thread 52 (Figure 12) being produced upon the screw 53. The distance between any two adjacent lines "a" is equal to one-half the circumference of the screw blank 50 being threaded. Thus, since the peripheries of said die rolls move past each other in opposing directions, the movement by each die periphery of said distance between adjacent lines "a" will rotate said blank 180 degrees.

On a conventional screw, as indicated in Figure 12, a thread root 54 is diametrically opposite to a thread ridge 55 at all times along the axis X of the screw 53. Accordingly, when the axis X' (Figure 10) of the screw blank 50 passes through the plane Y (Figures 10 and 13), defined by the axes of the die rolls 11 and 12, the roots on one die roll will be opposite the ridges on the other die roll. This arrangement of roots opposite ridges will be referred to hereinafter as being "in phase."

For the screw blank 50 to be moved or fed in a direction transverse to its axis, as downwardly, for example, the said phase between the roots and ridges on the die roll peripheries must move downwardly also, and this is accomplished by providing a faster peripheral speed on that one of said dies whose periphery moves downwardly between the dies, here die roll 12.

As shown in Figure 13 by plane Y, the proper phase occurs midway between each pair of adjacent lines "a." Thus, the number of slots 17 in the shell 16 is limited to the number of lines "a," or twice the number of starts "b," on the die roll which it encircles. The distance between said slots is, therefore, necessarily equal to the distance between a pair of adjacent lines "a" or an even multiple thereof. The feed shell 16 must be synchronized so that it has a slot 17 passing through said plane Y each time a phase passes through said plane Y. Due to the rolling movement of the screw blank 50 between the die rolls, the speed of said phase passage is equal to one-half the difference of the peripheral speeds of said dies.

Referring to Figure 10, it will be observed that the screw blank 50 has an outside diameter which is somewhat smaller than the outside diameter of the finished screw 53 after the thread rolling process is complete. Thus, if the trailing wall 58 of a slot 17 is snugly against the periphery of the blank 50 as it enters between the die rolls 11 and 12, the way it should be, then some means must be provided for accelerating the screw 53 to provide room for the expansion of its outside diameter during the rolling process. This expansion is represented by the distance between the center lines X and X' (Figure 10) of the finished screw 53 and the original blank 50, respectively. As shown in Figure 13, such expansion urges the screw axis X to pass through the plane Y in advance of said phase, which tends either to score the trailing wall 58 of the slot 17 or to jam the threads 52 on the screw 53.

Having recognized the problem and its cause, I have conceived several methods of accelerating the movement of said screw blank 50 and/or said phase with respect to the movement of the slot 17, as said blank 50 is engaged between the opposing surfaces of the die rolls 11 and 12, and thereby overcoming the problem. One such method is produced by slightly increasing, as by 1%, the diameter of the faster moving of the two rolls without changing any other aspect in the relationships between the shell 16 and the two rolls. This will cause the phase, hence the center line X of the screw 53, to move slightly faster than the slot 17 as it passes between the two die rolls. Here it is assumed that the die rolls had identical diameters before such increase in one diameter, and that they obtain their different peripheral speeds by being rotated at different angular speeds.

Another method of overcoming this problem, as shown in Figure 8, is to mount one of the die rolls, such as the die roll 11, so that it is axially slideable on its shaft 21. Resilient means, such as the springs 59, are provided upon both sides of said roll whereby the roll may be deflected axially a slight amount. Thus, when the increase in diameter of the screw blank 50 causes the blank to move ahead of the phase, the resiliently mounted roll shifts axially, which temporarily advances the phase and thereby prevents damage to the thread being produced on the screw.

Where the die rolls have the same rotational speed and the difference in their peripheral speeds is produced by having different diameters, approximately the same means may be used to prevent the injuries to the screw threads due to the expansion in the screw blank 50 during the rolling process. It will be recognized that, in order to maintain the same pitch and slope of the helical grooves on die rolls having different diameters, more starts "b" will be required on the larger diameter roll than on the smaller diameter roll. However, as in the case of the die rolls having the same diameters, the acceleration of the screw is accomplished without changing the number of starts. Such acceleration is effected by slightly reducing the ratio between the diameters of said rolls, or by using the springs 59, shown in Figure 8, and no other alteration is required.

Means, such as the guide strips 61 and 62 (Figures 1,

5 and 4), may be resiliently mounted upon a rod 63 parallel with the die shaft 22 for holding the screw blanks 50 within the slot 17 (Figure 9) as they approach a position between the die rolls 11 and 12. A spacer collar 64 encircles the die shaft 22 between the feed shell 16 and the coupling head 35. Oil, or any other convenient combination coolant and lubricant, may be supplied through means such as the pipe 65 to a point above the space between the die rolls 11 and 12 for feeding such lubricant onto the screw blanks as they are rolled between the die rolls 11 and 12.

Operation

As indicated generally in the above description, the machine 10 is prepared for operation by placing the proper sized die rolls 11 and 12 upon their respective die shafts 21 and 22, and by proper adjustment of the die rolls 11 and 12 with respect to each other. Such adjustment is effected by means of the guide rails 23 and 24, the clamping members 25 and 26, the locking collars 29 on the guide rods 27 and 28, and the connecting rods 36 and 37. It has been found that, in some instances, the tolerances in the bearings supporting the die shafts 21 and 22 may permit a deflection of one of the die shafts 21 and 22 with respect to the other to the extent of such tolerance during the rolling of the threads 52 upon the blanks 50. The result of this deflection is to place the die shafts 21 and 22 slightly out of a parallel attitude with respect to each other. In order to overcome this problem, the housing 13 is pivoted around the pivot pin 20 so that its shaft 21 is slightly out of parallel with the shaft 22 in housing 14, and both housings are then secured to the base 15. Thus, when the blanks 50 pass between the die rolls 11 and 12, the deflection of the shafts 21 and 22, such as it may be, renders them parallel. This correction for deflection may be provided for in the mounting of the housing 14, as well as in the mounting of the housing 13.

The feed shell 16 is adjusted by means of the worm 46 so that the slots 49 thereof will pass through the plane Y when the opposing peripheries of said die rolls are in phase. A means 30 for supplying the screw blanks 50 to the slots 17 is then provided and the machine 10 is ready for operation. It will be observed that the machine 10 in this particular embodiment slopes rearwardly and downwardly at an angle of between approximately 10° and 15°, as shown in Figure 2. The purpose of this is to utilize gravity in preventing the accidental discharge of the screw blanks 50 from the front ends of said slots 17, particularly where the screw blanks are provided with heads.

In order to overcome the scoring of the trailing wall 58 of the slots 17 by the screw threads 52 as the diameters of the blanks 50 expand during the rolling process, 53 said screws are accelerated as they advance between the die rolls 11 and 12 slightly faster than the movement of the slots 17. This is accomplished as stated above, by increasing slightly the diameter of the faster moving of said die rolls, or by permitting an axial shift of one of said die rolls with respect to the other. In either case, the phase is accelerated by an amount equal to one-half the increase in the thickness of said screw blank as the thread 52 is rolled into said blank.

If, as stated above, the differential in peripheral speeds 65 is accomplished by having different diameters for the die rolls 11 and 12, the acceleration in the advancement of the screw blanks 50 between the die rolls 11 and 12 may be accomplished by substantially the same methods. Whether the difference in peripheral speeds is accomplished by a difference in the diameters or by a difference in the rotational speeds of said die rolls, the number of starts "b" and the helical slope of the helical grooves 51 remain the same in applying either method of overcoming or avoiding injury to the screw threads 52 from scoring or jamming.

If it becomes desirable to change the pitch and/or diameter of the screw to be produced by the machine 10, new die rolls 11 and 12 must be provided, and substantially the same adjustments must be made as discussed hereinabove in detail.

The relative position of the feed shell 16 with respect to the die roll 12, which it encircles in this particular embodiment, may be adjusted circumferentially by means of the adjustment head 48, either while the machine is standing idle or is in operation. However, when such adjustment has been made, the feed shell 16 will then rotate, due to its geared connection with the die shaft 22, at a constant speed. Likewise, said rolls 11 and 12 will also be rotated at constant speeds in order to avoid an unintentional and undesirable shift in the phase relationship between the helical grooves on the two die rolls. Once this phase relationship has been established, it will remain constant until changed by manual operation of the worm gear 46 and the resulting rotation of the rear ring 44.

Although a particular, preferred embodiment of my invention has been disclosed hereinabove for illustrative purposes, it will be understood that variations and modifications thereof which do not depart from the scope of such disclosure are fully contemplated unless specifically stated to the contrary in the appended claims.

I claim:

1. A machine for cold rolling threads onto screw blanks, comprising: a pair of radially aligned die rolls having substantially parallel axes and a plurality of adjacent and uniform helical grooves of identical pitch and slope disposed along their peripheries, the distance between said peripheries being less than the diameter of said blanks, and thereby defining a zone of engagement between each blank and said peripheries, said blanks having a position of entry into said zone parallel with said axes; drive means for rotating said rolls simultaneously in the same rotational direction at different peripheral speeds, whereby a plurality of similar phases in the relationship between said grooves will occur adjacent to said position of entry at uniform intervals and then move at a constant rate of speed through said zone transversely of said axes; a cylindrical feed shell concentrically encircling one of said rolls and moving through said zone, said shell having a plurality of radially disposed, parallel slots therethrough, each slot being circumferentially wider than the diameter of said blank; driven means actuated

by said drive means for positively rotating said shell at a peripheral speed substantially equal to half the difference between said peripheral speeds of said rolls, said slots being moved between said rolls in the same direction as the faster moving one of said peripheries and at approximately the same rate as said phases, said blanks being moved into said position of entry by said shell when and only when one of said similar phases in said grooves occurs adjacent said position of entry; and said driven means including means in the form of positively engaged elements for adjusting the drive relation between said shell and said one roll for adjusting the relative positions of said slots and said phases within said zone.

5 2. A machine according to claim 1 wherein said rolls are secured to drive shafts and including means for rotating said drive shafts at a predetermined speed ratio with respect to each other; and wherein said positively engaged elements include an external gear secured to the drive shaft for said one roll, first and second ring gears coaxially encircling said external gear and having different pitches, said first gear being secured to said shell and said second gear being held against rotation with said shell, a plurality of planet gears engaged between said external gear and said ring gears, whereby rotation of said external gear effects a rotation of said second gear with respect to said first gear.

10 3. A machine according to claim 2 wherein said first ring gear has external teeth; and including a worm meshing with the external teeth on said first ring gear and means for manually rotating said worm, whereby said shell is rotated with respect to said one roll to adjust the relative positions of said slots and said phase points within the zone defined by the bite of said rolls.
